UNITED STATES PATENT OFFICE

ALFRED WINKLER AND MAX DÜNNEBIER, OF NEUWIED, GERMANY

APPARATUS FOR THE WITHDRAWAL OF SHEETS OR THE LIKE

Application filed August 31, 1929, Serial No. 389,730, and in Germany September 1, 1928.

One object of this invention is the provision of improved apparatus for the withdrawal of the lowermost sheet or the like from a stack of single or folded sheets, or of 5 groups or bundles of sheets or leaves folded together, and the invention relates more particularly to apparatus in which the withdrawal is effected by pulling the sheet from beneath the stack in a direction diagonal to 10 the sheet or approximately in that direction, and in which the sheet withdrawn from the stack is moved in a direction which is approximately opposite to the direction of its withdrawal from the stack. Such arrangements are employed mainly in the handling 15 of sheets that have been folded once or several times and have to be withdrawn individually from a stack from below, as is the case, for example, in newspaper inserting or 20 assembling machines. For the purpose of lessening the pressure resting upon the lowest sheet in the stack an inclined position of the stack has proved to be the most favorable or even the only practical one. In this connection it is necessary to place the sheets in 25 the inclined stack in such manner that they have their longitudinal and transverse folds resting against the stack stops, so that the corner formed by these two folds is situated 30 lowest. The resting of the folds against the stack stops produces a far more uniform position of the sheets in the stack than if the open and frequently irregular edges were to rest against such stops. Furthermore, since 35 in the case of doubly folded sheets, for example in the case of newspapers, the separation of one sheet from the stack is most advantageously commenced at the corner formed by the two folds or else, in case of 40 sheets folded once, at the corner formed by one fold and one open edge, because a separation can be more easily and positively effected at this point. It is therefore necessary to grip the lowermost sheet by the corner that is situated lowest and which is at 45 the same time also the lowest corner of the stack, in order first to separate this corner from the one situated above it and then to pull the sheet from beneath the stack.

50 The optional handling of single and of

folded sheets in one and the same apparatus requires, in addition, a particular guidance of the sheet after it has been withdrawn from the stack. Folded sheets must under no circumstances undergo a simultaneous bending 55 in different directions, as displacements within the sheet layers thus occur, which during the passage between pairs of guide rollers may easily result in wrinkling and the production of folds. Structural difficulties, however, prevent the further conveyance of the sheet withdrawn from beneath the stack in the same direction of motion as that of this withdrawal. The sheet must therefore be guided into a new direction in 60 such manner that it is conducted between draw-in rollers which, bending it only once, impart to it a new direction of motion, which is in most cases approximately opposite to that of the withdrawal from beneath the 65 stack, but extends in a horizontal plane. In this manner the sheet is conveyed back under the stack.

For the handling of single sheets without folds similar apparatus have become known. 70 For example, German Patent 276,374 shows means for the withdrawal of the lowest sheet from a stack. In that connection we are concerned with the drawing-in of sheets or blanks for the manufacture of envelopes into 75 a folding machine, i. e., with sheets or blanks of relatively great flexibility, which furthermore admit of the employment of a perpendicular stack because in that case the weight which rests upon the lowest sheet that is to be withdrawn is not too great and because there is no question of an imprinting of the sheets with consequent increase in the friction. In 80 this apparatus use is made of two discs with a V-shaped excision, which discs rotate contrary to one another and upon which the stack rests at its front edge. At every rotation of the discs this front edge of the sheet which is lowest is drawn through the excisions of the disc by means of a suction device, so that the discs in their further rotation come to be 85 above this sheet. At the same time the sheet corner which has thus been bent away is brought, by the suction device itself, between a pair of draw-in rollers which receive it 90

and thereby withdraw the sheet from beneath the stack in order to conduct it to further guides and conveyor means in which it assumes a direction of motion which is opposite to that which it has at its withdrawal from the stack.

Such an apparatus fails as soon as the stiffness of the sheets exceeds a certain degree, as is the case, for example, with newspapers that have many pages and are folded double. In the case of such sheets the guidance into a new position must, in view of the low flexibility, take place about a roller of relatively large diameter, and neither a suction device 15 nor a needle apparatus operates with sufficient positiveness to bend the large corner surface of each sheet away so far that it gets between the large upper roller and its co-operating under roller and is positively seized between the two.

On the other hand, the apparatus according to the present invention admits of the handling of sheets of the two types mentioned, i. e., of single sheets that have not 25 been folded and of single or multiple sheets that have been folded once or several times. It depends upon the employment of two bell-shaped devices which rotate contrary to one another and which are generally of truncated cone shape and are arranged directly beneath the stack symmetrically on both sides of an imaginary line drawn through the lower corner of the stack in the direction of withdrawal of the sheet, in such a manner that 30 the lowest sheet of the stack rests upon said devices with its fold edges that form the lower corner. In their upper faces and in their peripheral surfaces the bell-shaped devices have excisions of such a kind that at 35 their rotation below the lowest sheet, which has been bulged out or lifted off only to a small extent within the plane of its lowest edge by means of a needle apparatus or a suction device, they penetrate into the stack 40 simultaneously from both sides and at their further rotation convey this front edge of the lowest sheet between their conical peripheral surface and an upper roller which operates with an under roller. In this bending-down process the foremost point of the 45 bending-down sheet corner enters an excision of the under roller, so that it is seized between the upper roller and the under roller, and the sheet is thereby drawn out from beneath 50 the stack.

The novel action of the apparatus in accordance with the present invention, in comparison with other known arrangements consists not merely in the fact that the 60 bending-down of the sheet edge between the draw-in rollers by the bells takes place with absolute positiveness even in the case of very stiff sheets, but, on the contrary, it is also particularly important that the bells assure the 65 bending-down of the sheet with a bending-

edge which remains absolutely constant in the case of each sheet and that they do not admit of any accidental shifting of this bending-edge, a circumstance which can easily occur in apparatus operating with a so-called "horn disc", in which the shifting of the bending-edge and the alteration of the bending-curve may assume such an extent that the point of the work-piece no longer reaches the under roller of the pair of draw-in rollers, 70 which naturally has the consequence that the sheet is not seized at all by the latter rollers and consequently is not withdrawn from the stack.

In order to assure the perfect application 80 of the bent-down sheet corner against the upper draw-in-roller, there is further provided between the two bells an application device which applies the outermost point of the sheet edge completely against the upper 85 draw-in roller and holds it fast until it is seized by the under roller.

One form of the improved apparatus is illustrated in the drawings whereon:—

Fig. 1 is a vertical longitudinal section of 90 the apparatus taken on the line I—I of Fig. 2;

Fig. 2 is a view looking in the direction of the arrow II of Fig. 1;

Fig. 3 is a side view of one of the bells 95 looking in the direction of the arrow III of Fig. 2.

Upon an inclined stack plate 1 a sheet stack 2, is supported and it is assumed in the example shown in the drawings that the apparatus is handling doubly folded sheets, for example, newspapers, which have a simple transverse fold at 3 (Fig. 2) and a longitudinal fold 4 that lies double. The corner 5 that is formed by these two folds is accordingly situated at the lowermost part of the stack 2. The position of the folded sheets in the stack is assured by the stack stops 6 and 6' in such manner that the transverse folds 3 rest against the stop 6 and the longitudinal folds 4 rest against the stop 6'. The diagonal positioning of the stack, which is well-known per se diminishes the friction that occurs during the withdrawal of the lowermost sheet from the stack. On the other 110 hand the engagement of the folded edges 3 and 4 against the stops 6 and 6' assures a uniform positioning of the sheets in the stack. However, the corner 5, which is most favorable for the starting of the separation of the 115 lowest sheet from the stack and which is formed by the transverse fold 3 and the longitudinal fold 4 is located at the lowest point so that the withdrawal of the lowest sheet from beneath the stack must take place in 120 the direction indicated by its inclined or oblique position, i. e., by its inclination to the horizontal. The necessary means for this withdrawal do not for structural reasons permit an immediate further conveyance of the 125

130

work-piece in the direction of withdrawal. The direction must therefore be changed, and this change of direction must be so effected that even thick sheets, for example, news-papers containing many pages, are not wrinkled, creased or folded. These reasons have already led, in the case of known apparatus, to the employment of a pair of draw-in rollers 7, 8 situated under the stack, of which pair the upper roller 7 has such a diameter that the thickest sheet that is passed around it receives no damage due to the bending necessary in the process. With the increase in the diameter of the upper roller 7, however, there is also an increase in the superficial area of the edge of the lowest sheet which must be bent over to bring it between this upper roller 7 and its co-operating under roller 8. The magnitude of the bending-over angle is also increased, and with increased thickness of the sheets, the resistance to bending also increases. Neither a suction device nor a needle apparatus nor any other hitherto known device assures per se a positive bending-over of the sheet corner and its introduction between the draw-in rollers. In accordance with the present invention the following apparatus is therefore provided for this purpose.

30 The lowest corner 5 of the lowest sheet of the stack and thereby also that of the entire stack 2 rests with the edges 3 and 4, by which it is formed upon the upper surface of the bells 9 and 10, which bells 9 and 10 are situated in front of the upper draw-in roller 7, symmetrically on both sides of an imaginary line extending through the lowest sheet corner 5 and in the plane of the lowest sheet of the stack. The faces of the said bells are situated in the same plane as the stack plate 1. These bells 9, 10 are somewhat in the form of a truncated hollow cone, but their peripheral surfaces are curved so as to extend concentrically or approximately concentrically with the peripheral surface of the roller 7. In their faces and peripheral surfaces excisions 9' and 10' respectively are formed in such a way that there is formed by each excision in the face a tongue 11, which tongues, at the rotation of the bells in the direction of the arrows (Fig. 2), penetrate laterally under the lowest sheet, as long as its position remains unchanged, into its edges 3 and 4 in such a manner that these edges represent a chord of the circular path of the tongues. Between the two bells 9 and 10 there is provided a suitable device—in the example shown in the drawings, a needle apparatus 12—which seizes the lowest sheet of the stack 60 in the vicinity of its edge 5 and, by displacement upwards, bulges it downwardly away from the next sheet in such manner that it assumes approximately the position shown in broken lines in Fig. 1 of the drawings, so that between the lowermost sheet and the one

just above it there is formed a recess 13 into which the tongues 11 of the rotating bells 9 and 10 penetrate simultaneously from both sides, and at a rather acute angle, so that this penetration is assured even if the recess 13 is very narrow. On further rotation of the bells the sheet's edges 3 and 4 are seized by the edges 14 of the excisions 9' and 10' which extend in the peripheral surfaces of the bells. In consequence thereof, since the needle apparatus 12 has in the meantime moved back, the foremost corner 5 of the lowest work-piece is bent down through the excisions 9' and 10' in the faces of the bells in such a way that it must necessarily lie between the peripheral surfaces of the bells and the peripheral surface of the roller 7. In this process, as distinguished from other known methods, the bent down part of the sheet is in no way damaged or displaced in the narrow space between the bells and the roller 7; nor can the bending curve of the sheet edge change appreciably in the interval between the bells and the roller 7. This is of particular importance, because the foremost point of the edge 5 must arrive with positiveness in a recess 8' of the hollow under draw-in roller 7 and thereby be completely pulled out from beneath the stack. It is evident that a displacement of the bending edge in the direction of the corner 5, i. e., too great a deviation of the bending curve from the surface of the roller 7, might cause the foremost corner of the sheet to fail to enter the recess 8' of the cylinder 8 so that the sheet would not be removed from the stack.

In order positively to assure the application of the bent-down sheet edge against the upper roller 7 and its entrance into the excision 8' of the under roller 8 even in the case of very thick sheets, a special rotating application device is further provided between and below the bells 9 and 10. This device consists of round iron arms 15 which are screwed into a hub piece 17 fastened on the shaft 16, and each have an arc-shaped bent-over portion 18 arranged eccentrically to the axis of rotation 16. On the rotation of the application device, in a clockwise direction (Fig. 2), the portions 18 engage any bent sheet portion that may possibly be too far distant from the upper roller 7, and apply it against the said roller so that it must positively enter the excision 8' of the roller 8. According to the circumstances in any particular case, the shaft 17 of the application devices may be placed parallel to those of the bells 9 and 10 or else inclined thereto.

As being irrelevant for the actual invention, the drives for the apparatus contrivance are not illustrated in the drawings. The drive of the under roller 8 may be effected directly from the upper roller 7 by way of spur gears, while it is assumed in the drawings that the bells 9 and 10 are driven in a

suitable manner by bevel gears 21 and 22 situated on the shafts 19 and 20, and that the application device is driven by means of a bevel gear 23 fastened upon its shaft 16.

5 For the operation of the apparatus it is of no importance how many revolutions or partial revolutions the upper roller 7 executes for the handling of each sheet as long as no particular work on each sheet is assigned to 10 it and no operating tools are driven from its shaft. In accordance with the example shown in the drawings, it is furthermore assumed that the under roller 8 executes two revolutions for the handling of each sheet, 15 while the bells 9 and 10 are provided with two excisions 9' and 10' each and therefore have to execute only half a revolution for the handling of one sheet. The same thing is true also of the application device, which 20 carries two arms 15, diametrically displaced with respect to each other and whose portions 18 attend to the actual application.

From the pair of rollers 7—8 the work-piece is conducted between a belt 25, passed 25 around the roller 24, and the roller 7 and is conveyed forward from this point in the manner that may be most suitable in each particular case. For the purpose of adaptation to the different thicknesses of the sheets 30 the rollers 8 and 24 are supported in levers 26 and 27 which are acted on by springs 28 and 29, so that they are both constantly pressed against the roller 7.

We claim:

35 1. Apparatus whereby the lowermost sheet is withdrawn in a diagonal direction from a stack of single or folded sheets or the like, comprising means for supporting the stack in an inclined position with one corner of the 40 stack at the foot of the incline, means for forming a recess between the lowermost sheet and the one next thereto, a tongue adapted to penetrate said recess to bend down the lowermost sheet at the said corner of the 45 stack, a relatively large main roller mounted beneath the stack, a relatively small counter-roller cooperating therewith and recessed centrally of its length to receive the corner of the sheet, and a rotary bell-shaped member 50 carrying said tongue and mounted on an axis substantially parallel to the perpendicular axis of the stack and having a curved peripheral surface adapted to lie close to and in concentric relation to the peripheral surface 55 of the main roller to bring the sheet into close and uniform contact with the main roller and to insert the corner of the sheet into the said recess in the counter-roller.

60 2. Apparatus whereby the lowermost sheet is withdrawn in a diagonal direction from a stack of single or folded sheets or the like, comprising means for forming a recess between the lowermost sheet and the one next thereto, tongues adapted to penetrate the two 65 opposite sides of said recess to bend down the

lowermost sheet, a main roller mounted beneath the stack, a recessed counter-roller co-operating therewith, and a pair of rotary bell-shaped members carrying said tongues and mounted on axes substantially parallel 70 to the perpendicular axis of the stack and with curved peripheral surfaces shaped and arranged to bend the sheets uniformly against the peripheral surface of the said main roller with the leading corner of the 75 sheet projecting into the range of the counter-roller.

3. Apparatus whereby the lowermost sheet is withdrawn in a diagonal direction from a stack of single or folded sheets or the like, comprising means for forming a recess between the lowermost sheet and the one next thereto, tongues adapted to penetrate the two opposite sides of said recess to bend down the lowermost sheet, a main roller mounted beneath the stack, a counter-roller co-operating therewith and recessed centrally of its 80 length to receive the leading corner of the sheet, and a pair of rotary members shaped to form said tongues and peripheral surfaces 85 curved and arranged to lie concentrically and close to the periphery of the main roller to bend the sheet against said roller and into the recess in the counter-roller.

4. Apparatus whereby the lowermost sheet is withdrawn in a diagonal direction from a stack of single or folded sheets or the like, comprising means for forming a recess between the lowermost sheet and the one next thereto, tongues adapted to penetrate said recess to bend down the lowermost sheet, a main roller mounted beneath the stack, a recessed counter-roller co-operating therewith, a pair of rotary bell-shaped members carrying said tongues and mounted on axes substantially parallel to the perpendicular axis of the stack and with their peripheral surfaces shaped and arranged to bend the sheets against the peripheral surface of the said main roller and into the 100 range of the counter-roller, and rotary means for holding the bent sheet in contact with the main roller before engagement of the sheet by the counter-roller.

5. Apparatus whereby the lowermost sheet is withdrawn in a diagonal direction from a stack of single or folded sheets or the like, comprising means for forming a recess between the lowermost sheet and the one next thereto, tongues adapted to penetrate said recess to bend down the lowermost sheet, a main roller mounted beneath the stack, a recessed counter-roller co-operating therewith, a pair of rotary members with excisions 110 therein to form said tongues and shaped with peripheral surfaces concentric to the peripheral surface of the main roller, and at least one rotary arm for engaging the bent sheet and temporarily holding same against the main roller.

6. Apparatus whereby the lowermost sheet is withdrawn in a diagonal direction from a stack of single or folded sheets or the like, comprising means for forming a recess between the lowermost sheet and the one next thereto, tongues adapted to penetrate said recess to bend down the lowermost sheet, a main roller mounted beneath the stack, a recessed counter-roller co-operating therewith, a pair of rotary bell-shaped members with excisions therein to form said tongues and having peripheral surfaces concentric to the main roller to bend the sheet towards said main roller and into the range of the counter-roller, at least one rotary arm mounted on an axis parallel to the axes of the bell-shaped members and an arc-shaped portion arranged eccentrically to said axis and carried by said arm for engaging the sheet and pressing same into close contact with the main roller preparatory to engagement of the sheet by the counter-roller.

In testimony whereof we have signed our names to this specification.
